UNITED STATES PATENT OFFICE.

JOHN O. JENKING, OF DETROIT, MICHIGAN.

BROACHING TOOL.

Application filed February 4, 1922. Serial No. 534,217.

To all whom it may concern:

Be it known that I, JOHN O. JENKING, citizen of the United States, residing at Detroit, county of Wayne, State of Michigan, have invented a certain new and useful Improvement in Broaching Tools; and declare the following to be a full, clear, and exact description of the same, such as will enable others skilled in the art to which it 10 pertains to make and use the same, reference being had to the accompanying drawings, which form a part of this specification.

My invention relates to broaching tools shown in the accompanying drawings and 15 more particularly described in the following specification and claim.

It is well known that when the cutters of an ordinary broaching tool become worn it is necessary to discard the tool at a great 20 loss.

It is the object therefore of this invention to provide a tool comprising a mandrel having a plurality of removable cutters, a removable pilot and a removable burnisher 25 sleeved thereon, so that when the cutters are worn or broken they may be replaced to prolong the life of the tool. So also the shank or mandrel may be made of a different grade of tool steel from the cutters sleeved 30 thereon thus greatly reducing the cost of manufacture.

With the foregoing and other objects in view which will appear as the description 35 proceeds the invention further resides in the combination and arrangement of parts and in the details of construction hereinafter described and claimed, it being understood that changes may be made in the precise embodiment of the invention herein 40 disclosed without departing from the spirit of the same.

In the drawings accompanying this specification:

Figure 1 is a side elevation of a broaching tool with parts broken away.

Figure 2 is an end elevation of the same viewed from the end of the tool fitted with a nut.

Figure 3 is a side elevation of the mandrel 50 shown in Figure 1 with the cutters, pilot, burnisher and the retaining nut removed.

Figure 4 is an end elevation of the same as viewed from the threaded end of the mandrel.

Figures 5 and 6 are side and front elevations of a fiber washer located between the cutters sleeved upon the mandrel.

Figure 7 is a cross-sectional view of a mandrel having a "round" shank to receive the cutters taken on or about line 60 7-7 of Figure 3.

Figure 8 is a similar sectional view of a modification indicating a shank elliptical in cross-section.

Figure 9 is a side elevation of the nut 65 for securing the cutters upon the shank of the mandrel.

Figure 10 is an end elevation of the same, showing the flattened portion to receive a 70 wrench.

Fig. 11 is a side elevation of the pilot showing a portion broken away.

Figure 12 is an end elevation of the same.

Figure 13 is a side elevation of a group 75 of three integral cutters.

Figure 14 is an end elevation of the cutters.

Figure 15 is a side elevation of a removable burnishing mandrel.

Figure 16 is an end elevation of the same. 80

Figure 17 is a side elevation of a pilot for an "angular" broach—with parts broken away.

Figure 18 is an end elevation of the same. 85

Figure 19 is a side elevation of a group 85 of three integral cutters for broaching an angular hole.

Figure 20 is an end elevation of the same showing the central elliptical opening to receive the corresponding shank of the supporting mandrel. 90

Figure 21 is a side elevation of a detachable burnishing member for angular broaching tools.

Figure 22 is an end elevation of the same. 95

Referring now to the letters of reference placed upon the drawings:

A, indicates a mandrel having a head A' slotted at A² for the passage of a transverse key to connect the mandrel with an operating member—not shown. The shank of the mandrel is threaded at A³ to receive a nut. B, is a pilot sleeved upon the shank and beveled at the ends as indicated at B'; C, is a plurality of cutters which may be in integral groups of any desired number;—the drawings showing groups of three cutters, between which may be sleeved fiber washers 100 105

D if desired. E, indicates a burnishing collar sleeved upon the shank and F is a nut,—flattened at opposite sides as at F' to receive a wrench,—screwed to the threaded end A³ of the shank to secure the several elements thereon. The mandrel indicated in Figure 3 has a circular shank, an elliptical shank A^a may be employed as indicated in Figure 8, to secure the cutters against rotation thereon. The cutters shown in the drawings are in groups of three, it will be obvious however that a plurality of single cutters may be employed or any desired number of cutters may form an integral unit.

To provide for broaching a square hole a polygonal pilot B^a, shown in Figures 17 and 18 is employed with correspondingly shaped cutters C^a, as shown in Figures 19 and 20 are used in place of the circular cutters C illustrated in Figures 13 and 14, and so also a square burnishing tool E^a (see Figure 21) is provided having an arc-shaped face E^b, extending longitudinally of the broach.

Having indicated the several parts by reference letters the construction and operation of the device will be readily understood.

For convenience in assembling the cutters they may be arbitrarily marked to indicate

the size, and numbered consecutively that they may be properly assembled for size and taper:—the group of cutters of smallest diameter being nearest the head of the broaching tool and so on. If one of the cutters should become broken or damaged it is only necessary to remove that particular group for replacement by another group. The life of the tool is thus greatly increased over the usual broaching tool with a corresponding reduction in cost.

Having thus described my invention what I claim is:

A broaching tool comprising a mandrel having an enlarged head at one end and threaded at its opposite end to receive a nut, a pilot sleeved upon the mandrel adjacent to the enlarged head, a plurality of groups of integral cutters sleeved upon the mandrel, an arc-shaped burnishing element sleeved upon the mandrel adjacent its screw-threaded portion, and a nut engaging the screw-threaded portion of the mandrel to secure the several elements thereon.

In testimony whereof, I sign this specification in the presence of two witnesses.

JOHN O. JENKING.
